[57] CLAIM

The ornamental design for an arm-chair, as shown and described.

DESCRIPTION

FIG. 1 illustrates an embodiment in accordance with the present invention, in a rear perspective view, having a C-shaped combined arm and leg support and rounded horizontal ribbing;

FIG. 2 is a frontal perspective view of the FIG. 1 embodiment, seen from a point to one side of the chair; FIG. 3 is a front perspective view of a modified embodiment, wherein simulated loose cushions are provided on the front surface of the chair instead of horizontal ribbing;

FIG. 4 is a side perspective view of the FIG. 2 embodiment; and

FIG. 5 is a rear perspective view.

FIG. 1.

FIG. 2.

FIG. 3.

FIG. 4

FIG. 5.
